UNITED STATES PATENT OFFICE.

WESTERN UNDERWOOD, OF SANTA ANA, CALIFORNIA, ASSIGNOR OF ONE-HALF TO
H. H. WALKER, OF LOS ANGELES, CALIFORNIA.

DESIGN FOR A GLOBE UNIT FOR STREET LIGHT.

Application filed February 26, 1924. Serial No. 8,738. Term of patent 7 years.

To all whom it may concern:

Be it known that I, WESTERN UNDERWOOD, a citizen of the United States, residing at Santa Ana, in the county of Orange and State of California, have invented a new, original, and ornamental Design for Globe Unit for Street Light, of which the following is a specification, reference being

had to the accompanying drawing, forming part thereof.

The figure is a perspective view of the globe unit for street light.

I claim:

The ornamental design for globe unit for street light, as shown.

WESTERN UNDERWOOD.
